UNITED STATES PATENT OFFICE.

CLEO F. BRADNEY, OF DENVER, COLORADO.

INTERNAL-COMBUSTION ENGINE.

Application filed April 21, 1923. Serial No. 633,740.

To all whom it may concern:

Be it known that I, CLEO F. BRADNEY, a citizen of the United States, residing at Denver, in the county of Denver and State 5 of Colorado, have invented certain new and useful Improvements in Internal-Combustion Engines, of which the following is a specification.

My invention relates to internal combustion engines and an object of the invention 10 is to provide an engine of very simple construction which by the production of pressure energy alternately in opposite directions upon a reciprocating element secures 15 an equable and constantly active movement of a shaft with which said element is connected.

Another object of the invention is to provide an engine of the above described type 20 in which two reciprocating elements working in interconnected units co-operate to effect the rotation of the shaft by evenly balanced impulses.

A further object of the invention resides 25 in providing an explosion engine which owing to the small number of parts required in its operation, may be produced at low cost and maintained in perfect operative condition at a minimum expense, and still 30 other objects reside in providing an engine of the above described type the parts of which are readily accessible for repair and adjustment, in providing a simple and efficient arrangement for lubricating and cooling 35 the working parts of the engine, in providing an arrangement of ports and controlling devices which insure a substantially complete scavenging during each stroke of the reciprocating element, in directing the 40 fuel along a course which causes it to be preheated by the heat of the engine, and in other details of construction and novel arrangements of parts all of which will be fully described in the course of the following specification with reference to the accompanying drawings.

A distinctive feature of the invention is the arrangement of two pistons connected 50 by a hollow rod to operate conjointly in axially alined cylinders. Two separate combustion chambers formed between the cylinders and preferably exteriorly thereof are alternately charged and exhausted by the movement of a reciprocating valve element 55 which in order to properly time the passage of fuel to and from said chambers is pref-

erably composed of two co-operating members.

The cylinder is open at one end to provide for the direct connection of the connected pistons with a rotary crank shaft and the valves are operated by direct connection with the same shaft without the intermediary of cams or other adjustment requiring parts found in many engines of 65 similar character.

Another advantageous feature of the invention is that the fuel in its course to the compression spaces of the cylinders passes through the hollow piston stem and it is 70 a part of my invention to assemble two units each comprising axially alined cylinders and a piston element as hereinabove described in interconnection to co-operatively effect the rotation of one crank shaft 75 by successive power impulses at regular intervals in its rotary motion.

In assembling two units in this manner, one valve element is sufficient to regulate the admission of fuel to all the cylinders there- 80 of and by proper relative placement of the pistons in said units and a corresponding arrangement of the ports controlled by the movement of the valve element, the motive impulses of the engine may be timed so as 85 to act upon the reciprocating elements of the two units synchronously in opposite directions, with the effect that the crank shaft with which said elements are connected is subjected to two forces acting simultane- 90ously at opposite sides of its axis of rotation in the direction of its rotary motion.

Having thus briefly described the most distinctive features of my invention I will now proceed to explain the same in detail 95 with reference to the drawings in the several views of which corresponding parts are similarly designated and in which

Figure 1 represents a longitudinal section through an engine constructed in accordance 100 with my invention in which two units are co-operatively assembled as hereinabove described;

Figure 2, a longitudinal section along the line 2-2, Figure 1;

Figure 3, a transverse section showing the combustion or firing chambers of the engine, taken on the line 3-3, Figure 1, and drawn to an enlarged scale;

Figure 4, a similarly enlarged section in 10 the plane indicated by the line 4-4, in Figure 1;

Figure 5, a fragmentary vertical section in either of the planes designated by the lines 5—5 in Figures 3 and 4;

5 Figure 6, an enlarged cross section along the line 6—6, Figure 1;

Figure 7, a similar section taken on the line 7—7, Figure 1;

10 Figures 8, 9 and 10, diagrammatic views showing in vertical section, the relative positions of the piston elements of the two units and of the valve members controlling the supply of motive fluid thereto; and

15 Figure 11, a section on the line 11—11, Figure 9.

15 Referring more specifically to the drawings, the reference characters A and B designate the two units of the duplex engine illustrated in Figure 1, each unit comprising two cylinders 5 and 6 connected in axial 20 alinement by an interposed coupling or union 7.

25 The union 7 and the thereto adjoining ends of the cylinders are provided with flanges for their connection by coupling bolts 8.

30 Each unit is closed at its upper end, and for convenience in manufacture the two units may to this end be provided with a single head 9 fastened in the usual manner by means of bolts 10. A second head 12 disposed in the lower cylinder of each unit is fastened at the lower end of a tubular core 13 axially coincident with the cylinders and rigidly connected to the upper head by 35 means of a bolt 14.

40 The head thus suspended is channeled and ported and the hollow core is likewise ported for the passage of motive fluid to and from the compression spaces of the engine as will hereinafter be more fully described.

45 Two pistons 15 and 16 fitted for reciprocation in the cylinders of each unit are connected by a hollow rod 17 which is slidably fitted around the core 13.

50 The coupling 7 between the cylinders of each unit has a restricted throat 18 through which the rod 17 passes in fluid tight engagement with a bushing 19 of anti-friction material. The coupling or unit provides the firing or combustion chambers in which, during the operation of the engine, the combustible charges intermittently supplied thereto, are ignited.

55 In order to simplify the construction of the engine but one coupling is used when two units are assembled for co-operation and it will be apparent that the construction of the coupling as shown in the drawings and hereinafter described, in so far as the arrangement of its chambers and passages is concerned, the same is in a single unit engine.

60 The two firing chambers designated in the drawings by the reference characters 20 and 21, are formed oppositely and separate from

each other as best shown in Figures 2 and 3 and they are in the operation of the engine alternately connected with a source of fuel supply through the intermediary of a valve-element which works in a chamber 22 extending lengthwise between the two units. 70

75 In the construction illustrated in the drawings the corresponding cylinders of the units are like their unions, formed en bloc and the three major component parts of the engine, namely: the connected upper cylinders, the common union and the connected lower cylinders are provided with central bores which are axially aligned and which conjointly form the cylindrical valve chamber which extends the entire length of the engine and which has a number of ports the arrangement of which will later be described in detail. 80

85 It is to be understood without further illustration that in a single unit engine, the valve chamber is in like manner formed exteriorly of the aligned cylinders.

90 The upper piston of the connected pair of each unit has an axial open-ended bore and is rigidly fastened upon the upper portion of the open ended tubular connecting rod extending in said bore. The lower piston is closed at its upper end and fastened at the lower end of the rod, and it has a skirt 95 which fits slidably in the cylinder and around the stationary head at the end of the hollow core.

95 Screwed in the lower end portion of the skirt and held in place by a flange 23 of angle section bolted at the extremity of the same, is a bearing 24 for the support of the pin 25 of a connecting rod 26 which extends downwardly through the open end of the lower cylinder for its connection with the 105 crank shaft 27.

100 The latter is mounted in bearings at opposite sides of a case 28 which as is usual in engines of this type, is partially filled with a lubricating oil and provides a support for 110 the cylinders which are fastened upon a flange at the upper edge of the case by bolts 29.

115 The valve-element of the engine hereinbefore referred to, comprises two tubular members 30 and 31 one of which is slidably fitted in the other and which are conjointly fitted for reciprocation in the cylindrical valve chamber. The two valves are operated by direct connection with the crank 120 shaft and the latter has to this end, two cranks 32 and 33 disposed between the cranks 34 and 35 of the pistons and connected with the valve-members by means of connecting rods 36 and 37. 125

130 The cylinders are provided with surrounding water jackets 38 connected by a corresponding passage 39 in the coupling, and the firing chambers in the latter are equipped with the usual spark plugs 40 for

the ignition of their charges through the medium of a timing element in an electric circuit in which the plugs are connected.

The inner valve member 30 is closed at its ends and both valve members are provided with ports which in the operation of the engine, register with each other and with ports connecting the valve chamber with the cylinders and the firing chambers, as will 10 hereinafter be more fully described.

The two cranks connected with the piston elements of the two units, are placed opposite each other at 180 degrees, and the two cranks of the valve-members are arranged 15 with relation to each other and the direction of rotation to compel the inner valve member to move slightly in advance of the other member, and they are disposed relative to the piston cranks to co-operate with the piston 20 tons in timing the admission of motive fluid to and from the firing and compression chambers.

Having thus described the general construction of the component elements of my improved engine, I will now proceed to explain the arrangement of its ports and passages relative to its cylinders, pistons and firing and valve chambers, and the successive steps in the operation at which said ports 30 and connections are brought in communication with each other for the passage of motive fluid to and from the chambers.

The stationary head 12 in the lower cylinder of each unit has a duct or passage 41 for 35 the connection of the hollow core 13 which in the operation serves as a conduit for the transference of motive fluid through the hollow piston rod to and from the compression spaces of the engine, with an intake port 42 in the wall of the cylinder, through the intermediary of a port 43 in the skirt of the lower piston.

The port 42 connects with a carburetor which as usual supplies the combustible mixture of air and carbon gases, and in a duplex engine of the type shown in the drawings, the two intake ports are connected with one pipe 44 leading from the carburetor, by means of a manifold 45.

50 The compression spaces of the engine hereinbefore repeatedly referred to, are in the upper cylinder the space 46 between the upper piston and the upper cylinder head, and in the lower cylinder the space 47 between the closed end of the lower piston and the suspended head 12.

The last mentioned head has in addition to the passage 41, a duct 48 connecting the compression space 47 with the valve chamber 60 when a port 49 in the piston comes in register with said space and opposite port 50 of the cylinder, and ports 51 and 52 of the valves 31 and 30 are likewise in register with the cylinder port 50.

65 The two firing chambers 21 and 20 are

connected respectively with the upper and lower cylinders by openings 53 and 54 as shown in Figures 4 and 5, and in the duplex engine, the two firing chambers common to both units, each connect with an upper cylinder of one unit and a lower cylinder of the other unit so that when a charge is ignited in either chamber the piston elements of the two units are moved synchronously in opposite directions, and the crank shaft is in consequence subjected to two equal impulses simultaneously acting in the direction of rotation at opposite sides of its axis.

The admission of motive fluid to the firing chambers is controlled by the valve element 80 and each chamber has a port opening in the valve chamber as shown at 55 and 56 in Figures 2, 3 and 11, and the two valve members have two pairs of ports 57 and 58 which at a certain point in their reciprocating movement register simultaneously with the port of the respective firing chamber, as illustrated in Figure 3.

The upper cylinder of each unit has an intake port 59 which connects with the carburetor and as in the lower cylinder hereinbefore described, the openings of the two upper cylinders in the duplex engine are connected to one conduit 60 leading from the carburetor, by means of a manifold 61.

A duct 62 in the upper piston of each unit has a port 63 adapted to register with the intake port 59, and a second port 64 which simultaneously registers with a port 65 in the stationary hollow core 13 inside the tubular piston rod 17.

Another passage 66 in the piston connects its interior with a port 67 between the cylinder and the valve chamber at the same time that the port 64 of the passage 62 connects 105 with the intake port 59 as hereinbefore described, and the valve members 31 and 30 have two ports 68 and 69 adapted to simultaneously register with the port 67.

In the duplex engine two ports in each 110 valve member are brought in register with opposite ports of the valve chambers connecting respectively with the upper cylinders of the two units at different periods in the operation of the engine as will hereinafter be more fully explained.

The stationary core of each unit has furthermore opposite ports 70 adapted to connect its interior with the lower compression space 47 and the port 65 at the upper end 120 of the core is intended to connect its interior with the upper compression space 46 through the medium of a passage 76 in the upper cylinder and a port 77 which registers with the port 65 when the respective piston element 125 approaches the end of its downward stroke.

Each cylinder is provided with upper and lower exhaust ports 71 and 72 which are alternately covered and uncovered by the respective pistons in the operation of the en- 130

gine, and corresponding exhaust ports of the two units of the duplex engine are preferably connected by manifolds 73 and 74 shown in Figures 2 and 7.

Having thus described the mechanical construction of my improved engine, I will now proceed to explain its operation by reference to Figures 8 and 11 of the drawings.

In Figure 8, the piston elements of the two units are shown as moving in the direction of the arrows 75 and 76, that of the unit at the right hand side of the engine being near the end of its upward stroke and that of the other unit being in a corresponding position near the end of its downward stroke. With the pistons thus positioned, the charge compressed in the upper compression space 46 of the right hand unit by the upward movement of the piston element passes from the space through the duct 66 of the piston 15, the port 67 in the cylinder wall and the ports 68 and 69 of the valve members, into the valve chamber and the charge simultaneously compressed in the lower compression space 47 of the left hand unit enters the valve chamber by means of the duct 48 of the lower piston, the port 50 in the cylinder wall and the ports 51 and 52 of the valve members.

The ports 58 and 57 of the valve members are at the same time in a position in which they partially register with the port 56 of the firing chamber 20 which communicates with the lower cylinder of the right hand unit and the upper cylinder of the other unit and during the continued movement of the crank shaft to its upper dead center, said ports are entirely opened and the charge of compressed fuel is completely discharged from the valve chamber into the firing chamber above referred to.

With the elements of the engine in the above described position as illustrated in Figures 1, 2 and 8, the duct 62 of the upper piston of the unit at the right hand side of the engine connects the intake port 59 of the respective cylinder with the hollow core 13 and the fresh charge of fuel entering the latter passes through the ports 70 into the lower compression space 47. The duct 41 of the lower piston in the left hand unit of the engine is at the same time in register with the intake port 42 and the charge passes into the hollow core to enter the upper compression space 46 of the unit through the registering ports 56 and 77 and the passage 76 of the upper piston.

During the continued movement of the shaft, the connection between the compression spaces 46 and 47 of the two units and the valve chamber is rapidly closed by the upward motion of the outer valve member 31 while the piston cranks pass their dead center position, and immediately thereafter

the communication between the valve chamber and the firing chamber 20 is closed and the compressed charge thus confined in the latter, is ignited through the medium of the respective spark plug.

The force of expansion of the ignited fuel produces an impulse which causes the piston elements of the two units to move synchronously in opposite directions until they approach the end of their stroke when the above described conditions are reversed as illustrated in Figure 10.

In this position of the elements of the engine, the lower intake port of the right hand unit connects with the upper compression space as hereinbefore described with reference to the left hand unit and the upper intake port of the latter connects with the lower compression space. At the same time the fuel compressed in the compression space 47 of the right hand unit by movement of the lower piston toward the stationary head 12, is permitted to enter the firing chamber 21 which connects with the upper cylinder of the right hand unit and with the lower cylinder of the left hand unit and after the cranks of the piston elements have again passed their dead center positions, the charge confined in said chamber is ignited and impels the pistons in the opposite directions.

The exhaust ports which normally are covered by the pistons, are opened for the discharge of spent fuel when the pistons approach the end of their strokes and they remain open until after the pistons have commenced their return movement, and it will be evident that by this arrangement, the compression spaces are completely scavenged during each movement of the piston elements.

The two valve members operating jointly but one in advance of the other cooperate not only to rapidly cover and uncover the ports of the cylinders but to open said ports during their movement in one direction and continuously cover them during their return movement by a simple crank motion of comparatively small radius or throw.

The method of feeding the charge of fuel to the compression spaces of the cylinders through a central core is advantageous in that the fuel is preheated before compression and subsequent ignition and that by absorbing the heat, it cools the parts with which it comes in contact, and it will be seen that owing to the same feature of construction, liquid in the charge can not reach the crank case since it is completely vaporized by the heat of the engine before compression and that in consequence, the lubricant in the crank case is never thinned by leakage of raw fuel as frequently occurs in engines in which the compression spaces are in direct connection with the carburetor.

It will further be understood that inasmuch as the impulse produced by the ignition of the fuel in the combustion spaces acts directly upon the piston element for the compression of the fresh charges without the intermediary of the crank shaft or its bearings, an equable movement is obtained free from liability to knocks and waste motions, and wear of the connection between the piston element and the shaft and of the shaft and its bearings is materially reduced.

It will also be apparent that in the manner illustrated, an engine composed of more than two units may be assembled by means of integrally formed corresponding parts interconnected by bolts as shown and described.

Figure 9 of the drawings but indirectly referred to, in the preceding description, shows the parts in the position they occupy immediately after the valve members have reached the position shown in Figure 10, when by the continued movement of the pistons past their dead centers, the valve members are displaced to close the connection between the compression spaces of the units with the valve chamber, and the latter is fully connected with the respective firing chamber by complete registration of the ports 58, 57 and 55.

Having thus described my invention, what I claim and desire to secure by Letters Patent is:

1. In an internal combustion engine, axially alined piston chambers, ported pistons in said chambers, each chamber being provided with a port for the intake of fuel and having a compression space and a combustion space at opposite sides of the respective piston, and a rod connecting the pistons and having a passage co-operating with the ports of the chambers and the pistons to conduct fuel entering through the intake port of either piston chamber to the compression space of the other chamber at determinate periods in the movement of the pistons.

2. In an internal combustion engine, axially alined piston chambers provided with ports for the intake of fuel and having combustion spaces at their inner ends, ported pistons in said chambers, stationary heads co-operating with the pistons for the compression of fuel in spaces at the outer ends of the chambers, and a rod connecting the pistons and having a passage co-operating with the ports of the chambers and the pistons to conduct fuel entering through the port of either piston chamber to the compression space of the other chamber at determinate periods in the movement of the pistons.

3. In an internal combustion engine, axi-

ally alined piston chambers provided with ports for the intake of fuel and having combustion spaces at their inner ends, ported pistons in said chambers, a tubular rod connecting the pistons, a stationary head at the outer end of one of the piston chambers, a stationary head at the corresponding end of the other piston chamber, the heads co-operating with the pistons for the compression of fuel between them, and a hollow core fixed on the last mentioned head, within the piston stem, the various ports being arranged relative to each other and the interior of the rod to conduct fuel entering through the port of either piston chamber through the rod and the core, to the compression space of the other chamber at determinate periods in the movement of the pistons.

4. An internal combustion engine comprising axially alined piston chambers having combustion spaces at their inner ends, ported pistons in said chambers, a tubular rod connecting the pistons, a stationary head co-operating with one of the pistons for the compression of fuel in a space at the outer end of the respective piston chamber, a stationary channeled head co-operating with the other piston to compress fuel in a space at the outer end of the other piston chamber, the piston chambers being provided with ports for the passage of fuel from their compression spaces to the respective combustion spaces, a hollow ported core on the channeled head, within the piston rod, and a valve element controlling the passage of fuel from the compression space of each piston chamber to the combustion space of the same, the various ports and channels being arranged relative to each other and the interior of the piston rod to conduct fuel entering through the intake port of either piston chamber, through the rod and the core to the compression space of the other chamber at determinate periods in the movement of the pistons.

5. In an internal combustion engine, axially alined piston chambers provided with ports for the intake of fuel, ported pistons in said chambers, a tubular rod connecting the pistons, a stationary head co-operating with one of the pistons for the compression of fuel in a space of the respective piston chamber, a channeled head co-operating with the other piston to compress fuel in a space of the other piston chamber, and a ported hollow core fixed on the channeled head in rigid connection with the other head and extending in the piston rod, the various ports and channels being disposed relative to each other and the interior of the piston rod to conduct fuel entering through the intake port of either piston chamber, through the rod and the core, to the com-

pression space of the other piston chamber at determinate periods in the movement of the pistons.

6. An internal combustion engine comprising axially alined piston chambers provided with ports for the intake of fuel, ported pistons in the chambers, one of them provided with a trunk, a head co-operating with one of the pistons for the compression 10 of fuel in a space of the respective chamber, a channeled head within the trunk of the other piston, co-operating with said piston for the compression of fuel in the space between them, a crank shaft having a connection 15 with the trunk piston through the open end of the respective chamber, a tubular rod connecting the pistons, and a ported hollow core on the channeled head, within the piston rod, the various channels and ports being arranged relative to each other and the interior of the rod to conduct fuel entering through the intake port of either piston chamber, through the rod and the core to the compression space of the other chamber at 20 determinate periods in the movement of the pistons.

7. In an internal combustion engine, a unit comprising two sections having axially alined piston chambers, a section interposed 30 between the others, having two firing chambers connected respectively with the piston chambers at the inner ends thereof, interconnected pistons in the piston chambers, stationary heads co-operating with the pistons for the compression of fuel in spaces at the outer ends of the chambers, and a valve element adapted to provide a path for fuel from the compression spaces of the piston chambers to the firing chambers at determinate periods in the movement of the pistons.

8. An internal combustion engine comprising two units each having axially alined piston chambers, interconnected pistons in the chambers of each unit, each chamber being provided with ports for the ingress and egress of fuel and each chamber having a compression space and a combustion space at opposite sides of its respective piston, two firing chambers each connected with the combustion spaces of piston chambers at opposite ends of the two units, and a valve element adapted to connect the compression 45 spaces of piston chambers at opposite ends of the two units simultaneously with the firing chamber connected with the respective combustion spaces at determinate periods in the movement of the pistons.

9. An internal combustion engine comprising two units each having axially alined piston chambers, interconnected pistons in the chambers of each unit, each chamber being provided with ports for the ingress and egress of fuel and each chamber having a compression space and a combustion space

at opposite sides of the respective piston, two firing chambers each connected with the combustion spaces of piston chambers at opposing ends of the two units, a valve element adapted to connect the compression 70 spaces of piston chambers at opposite ends of the two units simultaneously with the firing chamber connected with the respective combustion spaces at determinate periods in the movement of the pistons, and means for 75 conducting fuel entering through the ingress ports of piston chambers at opposite ends of the units simultaneously to the compression spaces of the chambers at the other ends of the same.

10. An internal combustion engine comprising two units each having axially alined piston chambers provided with ports for the ingress and egress of fuel, interconnected pistons in the chambers of each unit, each chamber having a compression space and a combustion space at opposite sides of its piston, a valve chamber ported to provide a path for fuel from the compression spaces to the combustion spaces of the piston chambers of the two units, and a valve element moving in unison with the pistons and controlling the ports of the valve chamber to connect the compression spaces of piston chambers at opposite ends of the two units simultaneously with the respective combustion spaces at determinate periods in the movement of the pistons.

11. An internal combustion engine comprising two units each having axially alined piston chambers, provided with ports for the ingress and egress of fuel, interconnected pistons in the chambers of each unit, each chamber having a compression space and a combustion space at opposite sides of its piston, a valve chamber ported to provide a path for fuel from the compression spaces to the combustion spaces of the piston chambers of the two units, a crank shaft connected for rotation by the movement of the pistons, and a valve element having a crank-connection with the shaft and adapted to control the ports of the valve chamber so as to connect the compression spaces of piston chambers at opposite ends of the two units simultaneously with the respective combustion spaces at determinate periods in the movement of the pistons.

12. An internal combustion engine comprising two units each having axially alined piston chambers provided with ports for the ingress and egress of fuel, interconnected pistons in the chambers of each unit, each chamber having a compression space and a combustion space at opposite sides of its piston, two firing chambers each connected with the combustion spaces of piston chambers at opposite ends of the two units, a valve chamber having ports connecting with the firing chambers and with the compres- 125

5 sion spaces, and a valve element moving in unison with the pistons and adapted to control the ports of the valve chamber so as to connect the compression spaces of piston chambers at opposite ends of the two units simultaneously with one of the firing chambers.

13. An internal combustion engine comprising axially alined piston chambers 10 ported for the ingress and egress of fuel, a compression head at an end of one chamber, a ported hollow compression head at the opposite end of the other chamber, and hollow interconnected pistons having ports 15 co-operating with those of the piston chambers and the hollow compression head for the circulation of fuel in the operation of the engine.

14. An internal combustion engine comprising axially alined piston chambers 20 ported for the ingress and egress of fuel, a compression head at an end of one chamber, a ported hollow compression head at the opposite end of the other chamber, a ported connection between the hollow compression head and the piston chamber closed by the other head, hollow pistons having 25 ports co-operating with those of the piston chambers and the hollow compression head for the circulation of fuel in the operation of the engine, and a member connecting the pistons and controlling the passage of fuel through the ports of the connection between the heads.

35 15. An internal combustion engine comprising axially alined piston chambers 30 ported for the ingress and egress of fuel, a compression head at an end of one chamber, a ported hollow compression head at the opposite end of the other chamber, a

ported tube connecting the hollow compression head with the piston chamber closed by the other head, hollow pistons having ports co-operating with those of the piston chambers and the hollow compression head 45 for the circulation of fuel in the operation of the engine, and a tubular connection between the pistons, fitted around the ported connecting tube of the hollow compression head.

16. An internal combustion engine comprising axially alined piston chambers 50 ported for the ingress and egress of fuel, a compression head at an end of one chamber, a ported hollow compression head at the opposite end of the other chamber, rigidly 55 connected pistons connected in tandem for conjoint movement in the piston chambers and adapted to control the circulation of fuel through the ports of the chambers and of the hollow compression head, and means for conducting fuel from the compression spaces of the cylinders to the combustion spaces of the same.

17. An internal combustion engine comprising axially alined piston chambers 65 ported for the ingress and egress of fuel, a shaft, hollow and ported pistons rigidly connected in tandem for conjoint movement in the chambers in driving connection with the shaft, a compression head at an end of 70 one of the chambers, a ported compression head at the opposite head of the other chamber inside of the respective piston and means for conducting fuel from the compression spaces of the cylinders to the combustion 75 spaces of the same.

In testimony whereof I have affixed my signature.

CLEO F. BRADNEY.
